H. C. Pfingst,
INVENTOR

Leo Hayes
WITNESS:

BY *Victor J. Evans & Co.*

ATTORNEY

UNITED STATES PATENT OFFICE

HENRY C. PFINGST, OF LOUISVILLE, KENTUCKY

SMOKER'S ARTICLE

Application filed March 7, 1932. Serial No. 587,309.

This invention relates to smokers' articles and its general object is to provide an extinguisher for cigars and cigarettes as well as an ash tray, that not only is capable of use in expeditiously extinguishing a cigar or cigarette, but it can be done in a manner whereby the cigar or cigarette remains undamaged which of course is especially desirable with respect to a cigarette as the latter is easily damaged, with the result after the cigarette is extinguished by my device it can be re-lighted and used if desired.

A further object of the invention is to provide a device of the character set forth, that is simple in construction, inexpensive to manufacture, and extremely efficient in operation and service.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:—

Figure 1 is a sectional view taken approximately on line 1—1 of Figure 2.

Figure 2 is a top plan view of the device which forms the subject matter of the present invention.

Figure 3 is a perspective view of the extinguishing tube.

Figure 4 is a fragmentary sectional view showing the extinguishing tube in use.

Referring to the drawing in detail, the reference numeral 1 indicates the tray of my device which may be of any desired shape and size, but is shown as being provided with a flat bottom and an outwardly inclined circular upright wall 2 that has formed therewith an annular flange 3, the latter being flat so as to provide a substantial finger hold whereby

the device can be moved from place to place as will be apparent.

Secured to and rising centrally from the bottom is my extinguishing tube 4 that is reduced intermediate its ends to provide a restricted throat 5 and an outwardly flared mouth portion 6. The portion of the tube below the throat 5 is likewise outwardly flared so as to provide a substantial supporting means for the tube with respect to the bottom of the tray, and the lower portion is provided with diametrically arranged recesses 7 which are used for the purpose of removing ashes or the like which accumulate within the tube as will be noted upon inspection of Figure 4 which likewise shows the tube in use in extinguishing a cigarette.

From the above description and disclosure of the drawing, it will be obvious that I have provided a smoker's article in the form of a tray and an extinguisher, and when use is made of the latter, as for example as shown in Figure 4, the cigarette is moved gently down into the throat 5 to an extent whereby the throat completely surrounds and engages the burning end of the cigarette, with the result oxygen is cut off from the burning end, and naturally the fire is extinguished, without damaging the cigarette whatsoever, therefore it can be relighted if desired, after being removed from the tube. Of course the same operation is performed with respect to a cigar.

When the tube becomes filled with ashes and the like, it can be readily cleaned through the medium of the recesses 7.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A smoker's device comprising a tray, a tube secured to and rising from said tray and being reduced intermediate its ends to provide a restricted throat, an outwardly flared 5 mouth portion for said tube, and an outwardly flared bottom portion for said tube and being provided with diametrically arranged recesses extending through the lower edge thereof.

10 In testimony whereof I affix my signature.
HENRY C. PFINGST.
